COMBINED SMOKING PIPE RACK AND ACCESSORY UNIT

Charles T. Schmutte, 2438 Craig St., Sidney, Nebr.

Filed Mar. 18, 1963, Ser. No. 74,016

Term of patent 14 years

(Cl. D85—8)

FIG. 1

FIG. 2

FIG. 3

FIG. 4

FIG. 5

FIG. 6

FIG. 1 is a perspective view of a combined smoking pipe rack and accessory unit embodying my new design;
 FIG. 2 is a front elevational view thereof;
 FIG. 3 is a left side elevational view thereof;
 FIG. 4 is a right side elevational view thereof;
 FIG. 5 is a rear elevational view thereof;
 FIG. 6 is a top plan view thereof.

I claim:

The ornamental design for a combined smoking pipe rack and accessory unit, as shown.
